UNITED STATES PATENT OFFICE

GUST J. CHRISTENSON, OF CHICAGO, ILLINOIS, ASSIGNEE TO LOCOMOTIVE FIREBOX COMPANY, OF CHICAGO, ILLINOIS, A CORPORATION OF DELAWARE

THERMIC SIPHON AND METHOD OF MAKING THE SAME

Application filed December 14, 1929. Serial No. 414,028.

This invention relates to improvements in thermic siphons and method of making the same and it consists of the matters herein-after described and more particularly pointed out in the appended claims.

The thermic siphon with which my invention is more particularly concerned is of the kind best shown in the Nicholson Patent No. 1,337,720. Such a siphon is employed in the firebox of locomotive boilers and usually has its inlet neck opening through the throat sheet and its outlet or discharge, opening through the crown sheet. Siphons of this kind, increase the water steaming and circulating efficiencies of the boiler and act to keep the high end of the crown sheet flooded, even at water levels below normal.

Due to their construction, such siphons are expensive to produce. In the Nicholson patent before referred to, the siphon was formed from a single piece of sheet metal first cut to a pattern, and then folded along a predetermined line. Thereafter certain forming operations were carried out and the associated edges of the sheet were then welded together. This left a welded seam along one end of the body which extended down through the neck, the neck being transversely stayed for strength to the detriment of a free uninterrupted circulation. Such a siphon is difficult to produce, is expensive not only as to labor cost but also because of the accuracy necessary to make a perfect one and this, of course, often results in scrapping the siphon as imperfect following rigid tests.

In Patent No. 1,717,033 of June 11, 1929, granted to Walter H. Hinsch and myself, the siphon body was made of one or more parts and the tube was slit and formed for attachment to the body, the tube providing the inlet neck and a part of the closed bottom, the other part of the closed bottom being formed to a part of the body itself. Such a structure while reducing the cost of making siphons had certain disadvantages which the present invention overcomes.

The primary object of the invention is to provide a siphon of this kind which can be more easily made without the requirement of expensive apparatus, which contemplates

the production of different sizes of siphons with but a few number of parts and which provides a siphon wherein the welded seams are so disposed as to be in a manner protected against the abrasive wearing action of the products of combustion in the firebox in which they are installed.

Another object of the invention is to provide a siphon which can be made from a single piece of seamless tubing and a single metallic plate, coordinated to provide a siphon entirely bottomed by the tubing.

The invention consists generally of the steps, acts and sequence thereof and a siphon resulting therefrom whereby the above mentioned objects as well as others, together with the many advantages thereof that will hereinafter appear are attainable and my invention will be more readily understood by reference to the accompanying drawing which illustrates the improved siphon as well as the manner of making the same.

In the drawings:

Fig. 1 is a longitudinal vertical sectional view through a locomotive boiler firebox in which is located a siphon made in accordance with the preferred embodiment of my invention.

Fig. 2 is a transverse vertical sectional view through the same as taken on the line 2-2 of Fig. 1.

Fig. 3 is a horizontal sectional view through the same as taken on the line 3-3 of Fig. 1.

Fig. 4 is a view in elevation of a tube from which a part of my improved siphon is made and after it has been slit for the purpose of opening the same as will later appear.

Fig. 5 is a perspective view of the tube of Fig. 4 after it has had other operations performed thereon to make it ready to receive the siphon body as will later appear.

Fig. 6 is a fragmentary perspective view of the siphon body when ready for attachment to the tube, when in the condition shown in Fig. 5.

Generally stated I take a piece of seamless steel tubing of the desired length and slit the same along one side, the desired distance beginning at one end. I then open portions

of the tube along each side of the slit to form flanges thereon, spaced apart a distance equal to that of the side walls of the body to be later attached thereto. I then flatten that 5 end of the tube at which the slit begins, down to a width corresponding to the lateral spacing of the said flanges and then bend said end so that it extends at the desired angle with respect to the remainder of the tube. 10 I then take a piece of sheet metal such as boiler plate and cut it to such a pattern that when folded along its transverse median line, it will produce a body open at its top, bottom and one end and closed at the other end. 15 The open bottom end of said body is trimmed to fit or match up with the flanges and flattened end of the tube and is then butt welded thereto. In the formation of the flattened end of the tube and the body, suitable registering openings are provided to receive transverse staybolts and the siphon is then ready 20 for applying in place in a firebox.

Referring now in detail to the accompanying drawings, and more particularly to Figs. 25 4, 5 and 6 respectively, I provide a piece of seamless steel tubing 1 of proper length and diameter and slit the same longitudinally along one side as at 2, from one end as best shown in Fig. 4. Portions of the tube on 30 each side of the slit are then opened up to provide a pair of parallel laterally spaced flanges 3—3 on said tubing.

That end of the tube at which the slit 2 begins, is then flattened down as at 4 to a width 35 approximating the spacing of flanges 3 and is then bent in the plane of said flanges to approximately a right angle to provide an angularly disposed extension 5 on said tube as best shown in Fig. 5. In the flattened part 40 of the tube, near its free edges are formed registering staybolt openings 6. Instead of bending the slit tube after flattening the end thereof, I may bend said end of the tube and flatten it afterwards.

45 Coacting with the tube thus far formed is the body 7 which is made from a sheet of boiler plate or the like, cut to the proper pattern and then bent along a transverse median line to provide side walls 8—8 connected 50 together by a rounded end wall 9. In said walls are registering staybolt openings 10. From the above description taken in connection with Figs. 1 and 6 of the drawings, it is apparent that the body while being substantially 55 rectangular in shape, is open at the top and bottom and at the shorter end and is closed at its longer end. The bottom of each side wall as well as its shorter end are trimmed to match up with the flanges 3 and flattened end part 4 of the tube 1.

60 After the body 7 has been trimmed to fit the tube the associated edges of the body and tube are butt welded together as at 11 and staybolts 12 are applied in the registering holes 6 and 10 respectively of the tube and

body. In this respect it is pointed out that said staybolts may be applied to the tube and body before they are welded together, just as well as after they are welded together as above mentioned.

70 With the parts trimmed, staybolted and welded together as described, a siphon is provided as best illustrated in Fig. 1, wherein that end 13 of the tube 1 beyond the body 7 provides the inlet neck 1 for the siphon. To 75 apply such a siphon in place in the firebox, the crown sheet 14 thereof is provided with a longitudinally extending opening 15 to receive the top end of the body 7 and flattened part 5 of the tube and the same are then welded in place as at 16 from the interior of the firebox. The inner throat sheet 17 of the firebox is provided with an annularly corrugated diaphragm 18 to receive the end of the neck 13 which is thereafter welded in place 80 as at 19.

85 In forming the siphon, I prefer to make them oversize as to height and length of neck and then trim the siphon to fit the particular firebox in which it is to be installed. Thus I am not held to such close tolerances as are necessary in making the siphon from a single piece of sheet metal as in the Nicholson patent and it is not necessary to cut the bottom end of the body and the edges of the flanges of the tube along such irregular lines as in the Hirsch and Christenson patent before mentioned. With my improved structure, the lines of trimming are substantially regular ones and are easy to produce.

90 When my improved siphon is in place in a firebox as above mentioned, it is apparent that a structure is provided wherein the bottom of the siphon is inclined upwardly and rearwardly and the upper rear end is of a depth 95 less than the front end and merges into the bottom on a generous curve. Such a structure has advantages such as increased heating surface area and when arch brick are supported at one end upon said siphon, a larger arch is 100 permitted without bringing its front end too close to the crown sheet.

105 While in describing my invention, I have referred in detail to the form, arrangement and construction of the various parts thereof, as well as to a certain sequence in forming and assembling said parts, the same is to be considered merely as illustrative so that I do not wish to be limited thereto except as may be specifically set forth in the appended 110 claims.

115 I claim as my invention:—

120 1. The method of making thermic siphons which consists in providing an open top, flat hollow siphon body having side walls, in 125 slitting a seamless metallic tube throughout a portion of its length beginning at one end thereof, opening up portions of the tube upon opposite sides of the slit to provide parallel flanges thereon, forming the tube so that the 130

edges of its flanges fit the desired edges of the side walls of the body and terminates at one end in substantially the plane of the open top of said body and then welding the fitted edges of the body side walls and tube flanges together, the unslotted end of said tube projecting beyond the siphon body to form an inlet neck therefor.

2. The method of making thermic siphons which consists in providing an open top, flat hollow siphon body having side walls, in slitting a seamless metallic tube throughout a portion of its length beginning at one end thereof, opening up portions of the tube upon opposite sides of the slit to provide parallel flanges thereon, flattening said end of the tube down to a width approximating the spacing of said flanges thereon so that a portion of said end forms a continuation of said flanges, forming the edges of said flanges and their continuations on the flattened end of the tube so that they fit the desired edges of the body and then welding the fitted edges of the body and tube together, the unslotted end of the tube projecting beyond one end of the siphon body to form an inlet neck therefor.

3. The method of making thermic siphons which consists in providing an open top, flat hollow siphon body having side walls, in slitting a seamless metallic tube throughout a portion of its length, opening up portions of the tube upon opposite sides of the slit to provide parallel flanges thereon, forming said flanges so that the edges thereof fit the desired edges of the side walls of the body and then welding the fitted edges of the body side walls and said flanges together, one end of said tube terminating substantially at the top of the siphon body and the other end projecting beyond one end of the siphon body to form the inlet neck therefor.

4. The method of making thermic siphons which consists in providing a flat hollow body open at the top, bottom and one end and closed at the other end, in slitting a tube throughout a portion of its length beginning at one end thereof, opening up desired portions of the tube upon opposite sides of the slit to provide parallel flanges thereon, forming one end of said tube and a portion adjacent thereto to fit the open end and bottom respectively of the body and welding said open end and bottom of the body to said flanges of the tube, the other end of the tube projecting beyond the closed end of the body to form the inlet neck therefor.

5. The method of making thermic siphons which consists in providing a flat hollow siphon body open at the top, bottom and one end and closed at the other end, in slitting a tube throughout a portion of its length beginning at one end thereof, opening up desired portions of the tube upon opposite sides of the slit to provide parallel flanges thereon, bending one end of said tube in the

plane of the flanges to conform to the open end of the body, fitting said open end and bottom of the body to said bent end of the tube and the flanges thereon, and then welding said fitted part together, the other end of the tube extending beyond the closed end of the body to form an inlet neck therefor.

6. The method of making thermic siphons which consists in providing a flat hollow siphon body open at the top, bottom and one end and closed at the other end, in slitting a tube throughout a portion of its length beginning at one end thereof, opening up desired portions of the tube upon opposite sides of the slit to provide parallel flanges thereon, bending one end of said tube in the plane of the flanges to conform to the open end of the body, flattening said tube to a width equal to the spacing of said flanges, fitting said open end and bottom of the body to said bent flattened end part of the tube and the flanges thereon and then welding said fitted parts together, the other end of the tube extending beyond the closed end of the body to form an inlet neck therefor.

7. A siphon of the kind described embodying therein an upper hollow body portion and a lower tubular bottom member having flanges fitting desired portions of the body, one end of said tubular member terminating approximately in the plane of the top of the siphon and the other end of said tubular member extending beyond one end of the body to form an inlet neck therefor.

8. A siphon of the kind described embodying therein a flat hollow body open at the top, bottom and one end and closed at the other end, and a tube having spaced flanges conforming to said open end and bottom of said body and welded thereto, the other and closed end of said tube extending beyond the closed end of the body to form the inlet neck therefor.

9. A siphon of the kind described embodying therein a flat hollow body open at the top, bottom and one end and closed at the other end and a tube having spaced flanges and one end of said tube being flattened and bent in the plane of the flanges to receive the open end and bottom of said body which is secured thereto, the other and closed end of said tube extending beyond the closed end of the body to form the inlet neck therefor.

10. A siphon of the kind described embodying therein a flat hollow body open at the top, bottom and one end and closed at the other end and a tube having flanges engaged with and secured to the edges of said open bottom and end of the body, one end of said tube extending beyond the closed end of the body and forming the inlet neck therefor.

11. A siphon of the kind described embodying therein a flat hollow body open at the top, bottom and one end and closed at the other end and a tube having a flattened

and bent end fitting the open end of the body
and a portion of said tube adjacent said end
fitting the open bottom of the body and means
for attaching said portion of the tube and
body together and transverse staybolts in
said flattened end of the body, the other end
of the tube extending beyond the closed end
of the body to form an inlet end therefor.

In testimony whereof, I have hereunto set
10 my hand, this 10 day of December, 1929.

GUST J. CHRISTENSON.
